UNITED STATES PATENT OFFICE.

JOHANNES P. BECKER, OF BERKELEY, CALIFORNIA.

DESIGN FOR AN AUTO SIGNAL-LIGHT.

55,739.

Specification for Design.

Patented July 13, 1920.

Application filed July 22, 1919. Serial No. 312,584. Term of patent 14 years.

To all whom it may concern:

Be it known that I, JOHANNES P. BECKER, a citizen of the United States, residing at Berkeley, in the county of Alameda and State of California, have invented a new, original, and ornamental Design for an Auto Signal-Light, of which the following is a specification, reference being had to

the accompanying drawings, forming part thereof.

The figure is a perspective view of the auto signal light design.

I claim:—

The ornamental design for an auto signal light, as shown.

JOHANNES P. BECKER.
